United States Patent Office

Des. 183,175
Patented July 8, 1958

183,175

LOCKER HANDLE

Matt Monaco, Aurora, Ill.

Application May 27, 1957, Serial No. 46,361

Term of patent 14 years

(Cl. D10—8)

FIG. 1

FIG. 2

FIG. 4

I claim:

The ornamental design for a locker handle, substantially as shown.
